UNITED STATES PATENT OFFICE.

WILLIAM ADOLPHUS WILSON, OF BIRMINGHAM, ENGLAND.

SLIDING WINDOW AND ITS FRAME.

1,351,315.

Specification of Letters Patent. Patented Aug. 31, 1920.

Application filed June 9, 1920. Serial No. 387,713.

To all whom it may concern:

Be it known that I, WILLIAM ADOLPHUS WILSON, a subject of His Majesty the King of Great Britain and Ireland, residing at 3

Rawlings road, Birmingham, England, have invented new and useful Improvements in Sliding Windows and Their Frames, of which the following is a specification.

This invention has reference to sliding windows and the window frames therefor of that kind in which both sashes are mounted to turn on side pivots about midway of their height, on vertical runners adapted to move up and down in vertical side grooves of the sash frame, and the sash cords are fixed to these runners and are either so arranged with their pulleys that the weight of one sash counterbalances the weight of the other sash, or the cords pass over pulleys to the usual counterbalance weights. With this arrangement both sashes can be turned on the side pivots of their runners and cleaned inside and outside from the inside of the room. The pivoting of the sashes to the runners in the present instance is effected by the former being furnished with pivot pins which engage with slotted plates fixed to the sides of the runners and permit of the latter being removed from and replaced between the runners without disturbing the latter.

According to one part of my invention the wooden side strips of the front window frame which usually overlap the ordinary top and bottom sashes and form the front side of the groove up and down which the front sash slides, are for the depth of the lower sash hinged to the window frame so that when required, they may be turned back against the sides of the frame and permit of the bottom sash being turned about its pivots so as to enable the outside of the glass to be cleaned from inside the room. In a similar manner the top sash can be lowered and the bottom sash raised, and when the top sash is sufficiently lowered and the hinged side strips are turned back as aforesaid, the top sash can be similarly turned about its side pivots to enable its glass to be cleaned from inside the room; thus both the inside and the outside of the glass of both the top and bottom sashes can when in their lower position be cleaned from the inside of the room. My invention also comprises special arrangements of the pulleys and cords to be combined with the said window made with the sliding and swinging sashes as aforesaid so

as to insure both sashes moving together even if the top sash should stick in its guides. Moreover I provide improved means whereby the counterbalanced and swinging sashes can readily be removed from their runners without disturbing the latter and moreover said sashes can be securely locked when open to various amounts in addition to being locked when closed.

My invention is illustrated by the accompanying drawings of which—

Figure 1 is a front elevation partly in section of a pair of sliding sashes and a window frame according to my invention as seen from the inside of the room;

Fig. 2 is a sectional plan of the same taken through both sashes when the top sash is partly raised and the bottom sash is partly lowered;

Fig. 3 is a front elevation of a portion of a top sash and its runner;

Fig. 4 is a side elevation of the same;

Fig. 5 is a sectional side elevation of the window sashes and frame shown in Fig. 1 with the bottom sash partly turned into the room;

Fig. 6 is also a sectional side elevation of the same showing the bottom sash raised and the top sash lowered and turned on its side pivots into the room;

Fig. 7 is a sectional side elevation of the parting bead and two runners of the top and bottom sashes with the cords arranged according to a modification of my invention;

Fig. 8 is a front view of the parts shown in Fig. 7;

Fig. 9 is a sectional plan on a larger scale than Figs. 7 and 8 of the window frame and sashes and runners arranged with the cords and pulleys according to Figs. 7 and 8.

In carrying out my invention the bottom sash A is mounted at somewhere about midway of its height on side pivots 1 which engage in bearings in vertical runners 2, 3, 100 adapted to move up and down in vertical side grooves 4 of the sash frame B and the two sash cords 5, 6, are fixed to these runners 2, 3, instead of being fixed to the sash A as would be the usual arrangement. The lower portions of the two vertical wooden side strips of the window frame which usually overlap the top and bottom sashes and form the front sides of the grooves 4, up and down which the front sash A slides 110 (see Figs. 1 and 2) are for the depth of the lower frame each made of two pieces

- marked respectively 8 and 9 of which the strips 8 are screwed or otherwise fixed to the front of the window frame B so as to overlap the sides of the runners 2, 3, and 5 the strips 9 are hinged at 10 to these strips 8 so that when the strips 9 are turned against the sides of the bottom sash as in Fig. 2, they maintain the bottom sash in its vertical position, but when folded back 10 against the window frame as in Fig. 1 and as shown by dotted lines in Fig. 2, the bottom sash can be turned about its side pivots 1 and be reversed in position as shown by dotted lines in Fig. 5 so that the top rail 11 15 of the bottom sash A will now be at the bottom, and the bottom rail 12 of the bottom sash will now be at the top, and the outside of the glass will be inside and can readily be cleaned from the inside of the room. 20 Then when the bottom sash A has been turned back to its proper vertical position and the strips 9 have been turned back to their normal position against the sides of the sash and secured as by flush bolts or 25 other means, the sash A is ready for moving up or down.

The top sash C is similarly constructed, that is to say somewhere about midway of its height the sash C is mounted on side pivots 13 which are carried by runners 14, 15, which slide between the parting bead 16 of the window frame and the outside beads 17 of the same and to these runners 14, 15, the ends of the sash cords 5, 6, are fixed. 30 Now when it is desired to clean the top sash C the bottom sash A is first raised up as far as it will go as shown in Fig. 6 and the top sash C is pulled down as far as possible, as shown in Fig. 6. Now when the 40 two side strips 9 at the front of the window frame have been turned back on their hinges as aforesaid as is indicated by dotted lines in Fig. 2 the top sash C can be turned on its side pivots into the room as in Fig. 6 and reversed in position so that its top rail 18 will now be at the bottom and its bottom rail 19 will be at the top and the outside of the glass will be inside, so that it can readily be cleaned from the inside of the room, 45 and when so cleaned, then the sash C can be turned back to its normal position and slid up as aforesaid, as shown in Fig. 1. The portions 16 of the two parting beads which are immediately between the two runners 2 and 14 and 3 and 15 extend from the top to the bottom of the window frame 1, but the two narrow portions 20, between the two sashes only extend from the top of the frame to the top of the top rail of the bottom sash 60 so as not to interfere with the sashes swinging on their side pivots as aforesaid.

As before stated, the sashes A, C, can be counterbalanced as usual by cords passing over ordinary sash pulleys to counterbalance weights in pockets at the sides of the

window frames, or, and this is a feature of my invention, one sash can be made to counterbalance the other sash by the two sash cords 5, 6, of the two runners 2, 3, of the bottom sash A passing over top pulleys 21, 70 22, in the window frame and the ends of the cords 5, 6, being connected to the runners 14, 15, of the top sash C as in the arrangement illustrated in Figs. 1, 5 and 6, so that in this case no counterbalance weights are 75 required and the window frame B is less costly to construct besides saving the cost of the sash weights. In this arrangement of my invention the sashes A and C move simultaneously, one sash going up while the other sash goes down and in order to prevent a direct draft into the room from the bottom sash A when the top sash is moved down over a short distance for top ventilation, a horizontal flap 45 may be provided 80 and hinged to the bottom of the inside of the window frame B (see Fig. 1), this strip being adapted to turn up and close the narrow short space there would be between the bottom of the bottom sash A and the bottom 85 of the window frame B when the bottom sash is raised for a short distance to permit of top ventilation over the top sash as aforesaid, this horizontal flap 45 being adapted to turn up between the two side strips and being secured by flush bolts or any convenient means as will readily be understood.

In a modification of my invention instead of the cords 5, 6, which connect the vertical runners of the bottom sash to the vertical 100 runners of the top sash passing over the side pulleys 21, 22, on the top of the window frame so as to enable one sash to counterbalance the other one as aforesaid, the said cords and pulleys may be arranged for this purpose as I will now describe, so that although the top sash may stick and not run freely, it will be compelled to come down when the bottom sash is raised.

In this modification of my invention (see 110 Figs. 7, 8, and 9) the vertical wooden partition 16 at each side of the sash frame B is made wide enough to form a pulley stile for the independently revoluble cord pulleys which are marked respectively 23, 24, and 115 they are mounted side by side preferably on one and the same horizontal pin 25 at about midway of the height of the frame or otherwise about level with where the top rail of the bottom sash A meets the bottom rail of 120 the top sash C when both sashes are closed. The runners 14, 15, of the top sash are connected to the runners 2, 3, of the bottom sash at each side by two stranded wire cords or the like, one of which namely 26 is fixed as 125 at 27 to the bottom of the runner 14 of the top sash and passes over the side pulley 23, and has its other end 28 fixed to an attachment on the bottom of the runner 2 of the bottom sash and the other stranded wire 130

cord 29 or the like has one end 30 fixed to the top of the runner 14 of the top sash and passes under the other pulley 24 and then turns up and is fixed at 31 to an attachment on the top of the runner 2 of the bottom sash; thus by this arrangement the sashes A and C will counterbalance each other and the bottom sash A cannot be raised without at the same time lowering 10 the top sash C, as this is pulled down by the cord 29 when the bottom sash A is being raised.

A suitable device is provided for tensioning the stranded wire cords or the like. 15 This can conveniently be effected by one end of the wire such as the end 30 in Fig. 7 being formed into a loop and permanently fixed as by a cross screw to the top end of the runner 14 and the other end of the wire 20 being soldered or otherwise fixed to a short screw threaded wire stem 34 which passes through a slotted or other hole in a plate 35 fixed to the other runner 2. A nut 36 is provided on the wire 34 by which the wire 25 can be lengthened or shortened within certain limits to take up any stretch in the wire. This tensioning device is well known and I make no claim to it.

In order to fasten the sashes and prevent 30 them from being opened from the outside a peg may be provided in one or both sides adapted to pass through any one of a series 35 of holes in the hinged vertical wooden side strips 9 of the frame into a corresponding hole or holes in the runners.

In order to facilitate the removal of the sashes from the runners the side pivots on

the sashes are preferably each made with a head 38 and a narrow neck adapted to pass through a side slot 39 in a plate 40 (see 40 Fig. 7) which is fixed to the face of the runner, said necks engaging in bearings at the bottom of the slots. Thus to remove the sash from its runners the sash must be raised sufficiently for the hinge pins to pass 45 out of the side slots, but in order to secure the pivot pins in the slots until the sash is turned it is preferred for the top and bottom ends of each runner to be provided with laterally projecting inclined plates such as 50 41, 42, (see Figs. 3 and 4), these being arranged to engage with the corresponding rabbets 43, 44, formed on the sides of the sash and thus prevent the sash from being lifted independently of the runners unless 55 the sash is turned out of its normal position parallel with the runners.

What I claim as my invention and desire to secure by Letters Patent is:—

The combination with a window frame, 60 of an upper and lower sash mounted for sliding movement in said frame, a pair of independently revoluble pulleys mounted at the side of the frame intermediate its ends, a flexible strand led under one of the pulleys 65 and having its ends connected to the upper parts of the sashes and a second flexible strand led over the other pulley and having its ends connected to the lower parts of the sashes whereby a movement of either 70 sash compels movement of the other sash.

In testimony whereof I have signed my name to this specification.

WILLIAM ADOLPHUS WILSON.
